CUSHION UNDERFRAME

Stanley H. Fillion, Scarsdale, N. Y.

Application June 30, 1951, Serial No. 234,592

9 Claims. (Cl. 213—8)

1

This invention relates to cushion underframes for use on railway cars as a means for cushioning the forces applied to the couplers. More particularly, the invention is concerned with a novel cushion underframe, which is superior to prior similar underframes, in that it is of larger capacity and thus provides a better cushioning action and affords greater protection to the lading of the car, on which it is used. The new underframe is, accordingly, well adapted for use on cars carrying heavy permanent loads, such as motor generator sets, motor driven pumping equipment, etc.

Cushion underframes, as heretofore commonly constructed, include a draft and buffering column extending from end to end of the car between fixed longitudinal sills and connected at each end to a coupler. At each bolster, a center filler casting connecting the sections of the bolster on either side of the sills projects upwardly into the column and serves as an abutment for one end of a spring group having its other end engaged by an abutment on the column. The spring groups at opposite ends of the column resist its movement in either direction as a result of forces applied to the couplers and part of the forces is absorbed as friction between the column and its supporting means.

The prior underframe described affords an advantage over friction draft gears, in that the movement of the column does not contribute to train slack but the capacity of the underframe is not great enough to provide the desired protection of certain kinds of lading, such as the permanent installations previously mentioned. Also, forces applied to a coupler of a car equipped with the prior underframe are transmitted to the car structure at two places only, namely, the bolster center filler castings.

The present invention is directed to the provision of a novel cushion underframe, which is of greater capacity than such underframes as made heretofore and is so constructed that, when an oversolid blow is applied to the coupler, the force is transmitted to the car structure at at least three and, if desired, more points. The new underframe, accordingly, provides improved lading protection.

For a better understanding of the invention, reference may be made to the accompanying drawings, in which

Fig. 1 is a schematic view, partly in longitudinal horizontal section and partly in plan, of the new cushion underframe;

Fig. 2 is a view, partly in longitudinal horizontal section and partly in plan, of part of the new underframe;

Figs. 3 and 4 are sectional views on the lines 3—3 and 4—4, respectively, of Fig. 2; and

Figs. 5 and 6 are sectional views on the lines 5—5 and 6—6, respectively, of Fig. 3.

In the drawings, the new underframe is illustrated as installed on a railway car, which comprises fixed longitudinal sills 10 connected by end sills 11 and lying between the sections 12a,

12b of a bolster, the inner ends of which are connected by a center casting 13.

A draft and buffering column 14 is mounted between the sills 10 and may advantageously be made of a pair of Z-bars 14a, 14b, arranged with their top flanges abutting and connected together and their lower flanges extending outwardly. The column thus includes a pair of spaced vertical walls 15, 15. The column is supported for endwise movement between the sills on suitable angle members, which are attached to the inner faces of the sills and on which the flanges 16, 16 of the column rest.

At each end, the column is connected to the shank of a coupler in any desired way, and the connection may be such as to absorb shocks. In the construction illustrated, the shank of the coupler 17 is connected by a swivel connection to the front end of a yoke 18, which encircles a cushioning unit 19 made up of a plurality of flat rubber springs separated by divider plates. A follower 20 lies between the cushioning unit 19 and the front bar of the yoke, and the follower projects outwardly from the yoke and its ends engage stops 21 on cheek plates 22 secured to the inner faces of the sills. The walls 15 of the column are provided with longitudinal slots near their outer ends, and the cheek plates are similarly slotted, as indicated at 23. A slot 24, aligned with slots 23, is formed through the connection between the yoke and coupler shank, and a key 25 passes through the aligned slots in the walls, plates, and connection. The slots are somewhat wider than the key. Behind the rear bar of the yoke, is disposed a cushioning unit 26, made up of flat rubber springs separated by divider plates, and the rear end of unit 26 engages a follower 27 bearing at its inner side against stops 28 formed on reinforcing members 29 secured to the inner faces of walls 15.

The reinforcing members 29 are provided with aligned longitudinal slots 30, and the walls 15 are correspondingly slotted at 31. A key 32 extends through the slots in the members and walls, and its ends enter slots formed in cheek plates 33, attached to the inner faces of the sills, and through aligned slots in the sills. The ends of the key fit snugly in the slots in the cheek plates 33 and sills, but slots 30 and 31 are substantially longer than the key is wide. At its inner end, each reinforcing member is formed with a stop 34, and a follower 35, encircling key 32, extends inwardly with its end lying flush with the inner faces of stops 34.

A cushioning device, generally designated 36, is mounted between walls 15 inward from stops 34 and, in the construction shown, the cushioning device is made up of outer and inner double-acting friction draft gears 36a, 36b. If desired, a follower 37 is interposed between the outer end of gear 36a and stops 34 and follower 35. Similarly, at the inner end of gear 36b, a follower 38 may be interposed between the inner end of the gear and stops 39 on reinforcing members

40 mounted on the inner faces of walls 15 and similar to members 29. The walls 15 are provided with horizontal slots 41 aligned with similar slots 42 in the reinforcing members 40, and a key 43 projects through the aligned slots 41, 42 and passes through slots in cheek plates 44 secured to the inner faces of sills 10 and through aligned slots in the sills. The key fits snugly in the slots in the cheek plates and sills, while slots 41, 42 are substantially longer than the key is wide. A follower 45 encircles key 43 and projects outwardly therefrom with its end normally lying flush with the outer faces of stops 39.

At the other end of the column, the construction described is duplicated and the parts thereof are designated by the same numbers as above used but with prime marks.

The cushioning devices 36, 36' at opposite ends of the column are alike in capacity and travel and, when the underframe is in normal position, the distance a , a' between each outer key 32, 32' and the stops 28, 28' at the outer ends of the slots 31, 31' in walls 15, through which the key extends, is slightly less than the travel of the cushioning devices. Also, the distance b , b' between the outer keys 32, 32' and stops 34, 34' at the inner ends of the slots 31, 31' is equal to distance a , a' . The distance c , c' between each inner key 43, 43' and the stops 39, 39' at the outer ends of the slots 41, 41' in walls 15, through which the key projects is less than the travel of the gears and preferably slightly greater than the distance a , a' . The distance d , d' between the inner keys 43, 43' and stops 46, 46' at the inner ends of the slots 41, 41' is slightly less than the distance a , a' . In a specific embodiment of the invention, the travel of the cushioning devices 36, 36' may be 8 inches, in which event distances a , a' and b , b' may be 7.5 inches, distance c , c' 7.75 inches, and distance d , d' 7.25 inches.

With the construction described, the action is as follows: When a force in buff is applied to the coupler 17 at the right-hand end of the column, the coupler moves inwardly and the first action is to move yoke 18 inwardly to compress cushioning unit 26 against follower 27 held in place by stops 28. The force also tends to urge the column inwardly against the resistance of cushioning devices 36, 36', to which the force is transmitted by stops 34, 39', respectively. Movement of unit 36 as a whole is resisted by engagement of its inner end with follower 45 encircling inner key 43, and movement of cushioning device 36' as a whole is resisted by follower 35' encircling outer key 32'. However, if the force is relatively light, the column remains at rest and, when the force is removed, the cushioning unit 26 expands and restores the yoke and coupler to their original positions. If a similar light force in draft is applied to the coupler 17, it moves outwardly, drawing the yoke with it, and cushioning unit 19 is compressed against follower 20 bearing against stops 21. When the force is removed, unit 19 expands to restore the coupler and yoke to their original positions.

When a large force in buff is applied to the coupler 17, the inward movement of the yoke 18 compresses cushioning unit 26 and, as the compression proceeds, key 25 engages the inner ends of slots 23, so that a solid connection is made between the coupler 17 and the walls 15 of the column. The column then moves inwardly, and stops 34, acting on follower 31, compress cushioning device 36 against follower 38 held in place

5 by follower 45 encircling inner key 43. Similarly, stops 39' act through follower 38' to compress cushioning device 36' against follower 37', held in place by follower 35' encircling outer key 32'.

During most of the inward movement of the column, the applied force is transmitted to the fixed sills 10 through the inner key 43 near the point of application of the force and through the outer key 32' at the far end of the car. Just before the column has moved inwardly a distance equal to the travel of the cushioning devices 36, 36', the column is rigidly connected to the sills through either the outer key 32 at the near end, the inner key 43' at the far end, or through both keys. In the specific construction described, in which the distances a , a' and b , b' are 7.50 inches, distance c , c' is 7.75 inches, and distance d , d' is 7.25 inches, the distortion of the column between stops 34, through which the load is applied to cushioning device 36, and stops 39', through which the load is applied to cushioning device 36', is such as to increase distances c and d . As a result, stops 46' engage the inner key 43' at the remote end of the column, just before the column has moved inward a distance equal to the travel of the cushioning devices 36, 36', and stops 28 engage the outer key 32 at the near end of the car, either just before, just after, or at the same time that stops 46' engage the far inner key 43', depending upon the design of the structure. Accordingly, when a force in buff is applied to the coupler, the force is initially transmitted to the sills through keys 43 and 32' and, if the force is more than sufficient to move the column inward a distance greater than the travel of the cushioning devices 36, 36', the column is rigidly connected to the sills through either the inner key 43' at the remote end, the outer key 32 at the near end, or both these keys, before the cushioning devices 36, 36' have gone solid. Accordingly, in the construction described, the total forces of impact are transmitted to the sills and the car structure at three or four places and, by the use of additional cushioning devices and keys therefor, the number of places at which impact forces are transmitted to the car structure may be correspondingly increased.

When a force in draft is applied to the coupler 17, the reverse action takes place. Initially, after compression of the cushioning unit 19 within the yoke 18, the column begins to move outwardly and cushioning device 36 is compressed by stops 39 against follower 37 held in place by follower 35 mounted on outer key 32 at the near end of the car. Similarly, stops 34' act to compress cushioning device 36' against follower 38' held in place by follower 45' encircling the inner key 43' at the far end of the car. In draft, the forces transmitted through the yoke to the column are usually insufficient to cause stops 46 to engage the near inner key 43, or stops 28' to engage the far outer key 32'.

In order that the column may be more quickly restored to its initial position, after having been displaced therefrom by the application of a force in buff or draft applied to one of the couplers attached to the column, it may be desirable to equip the underframe with restoring means to supplement the restoring forces of the cushioning devices, and the underframe illustrated is provided with such means. Between the inner keys 43, 43', a cross member 47 is attached to the lower flanges of sills 10 to extend beneath the column. A pair of plates 48 are secured to the top of the cross member to extend verti-

cally and parallel to the walls 15 of the column. An upper horizontal plate 50 is secured to the top of plates 48, and a lower horizontal plate 51 is secured in recesses in the inner edges of plates 48. Plates 50, 51 project inwardly from plates 48, and their projecting portions are bored to receive a pair of pins 52. A follower 53 lies in front of the inner edges of plates 50, 51 and normally engages stops 54 secured to the inner faces of walls 15. The follower is bored for the passage of rods 55, which extend through the follower and have eyes, through which pins 52 pass. At their other ends, the rods pass through openings in a follower 56, which engages stops 57 secured in the inner faces of walls 15 of the column. The rods 55 have heads 55a beyond follower 56, and coil springs 58 encircle the rods and bear against followers 53, 56. When the column moves to the left (Fig. 1), stops 54 move follower 53 to compress the springs against follower 56, which is held against movement by the heads 55a on rods 55 anchored by pins 52 and the associated parts to the cross member 41 rigidly attached to sills 10. When the force applied to the coupler is removed, the springs expand to restore the column to its original position. When the column is displaced by a force in draft and moves to the right, the heads 55a on rods 55 cause the follower 56 to compress the springs 58 against the follower 53, which engages the ends of plates 50, 51 and is held against movement. When the force in draft is removed, the springs expand and act through follower 56 to restore the column to its original position.

I claim:

1. In a railway car having a frame, the combination of a draft and buffing column extending lengthwise of the car and supported for endwise movement on the frame, the column including spaced vertical walls having outer and inner pairs of aligned openings adjacent each end of the column, outer and inner keys passing through the respective pairs of openings and anchored at their ends on the frame, the keys being substantially narrower than the length of the openings, a pair of cushioning devices of equal travel within the column at opposite ends thereof, each device lying between the outer and inner keys at the adjacent end of the column, a follower on each key normally engaging the adjacent end of the adjacent cushioning device, stops mounted on the column walls, one at each end of each opening, the pairs of stops between the outer and inner keys at each end of the column normally engaging the ends of the adjacent cushioning device, the stops at opposite ends of the openings for each key being spaced from the key a distance less than the travel of the cushioning devices, and a coupler at each end of the column having its shank connected to the column.

2. In a railway car having a frame, the combination of a draft and buffing column extending lengthwise of the car and supported for endwise movement on the frame, the column including spaced vertical walls having outer and inner pairs of aligned openings adjacent each end of the column, outer and inner keys passing through the respective pairs of openings and anchored at their ends on the frame, the keys being substantially narrower than the length of the openings, a pair of cushioning devices of equal travel within the column at opposite ends thereof, each device lying between the outer and inner keys at the adjacent end of the column, 75

a follower on each key normally engaging the adjacent end of the adjacent cushioning device, stops mounted on the column walls, one at each end of each opening, the pairs of stops between the outer and inner keys at each end of the column normally engaging the ends of the adjacent cushioning device, the stops at opposite ends of the openings for each key being spaced from the key a distance less than the travel of the cushioning devices, spring means attached to the column and frame and resisting movement of the column in either direction from a central position, and a coupler at each end of the column having its shank connected to the column.

3. In a railway car having a frame, the combination of a draft and buffing column extending lengthwise of the car and supported for endwise movement on the frame, the column including spaced vertical walls having outer and inner pairs of aligned openings adjacent each end of the column, outer and inner keys passing through the respective pairs of openings and anchored at their ends on the frame, the keys being substantially narrower than the length of the openings, a pair of cushioning devices of equal travel within the column at opposite ends thereof, each device lying between the outer and inner keys at the adjacent end of the column, a follower on each key normally engaging the adjacent end of the adjacent cushioning device, stops mounted on the column walls, one at each end of each opening, the pairs of stops between the outer and inner keys at each end of the column normally engaging the ends of the adjacent cushioning device, the stops at opposite ends of the openings for each key being spaced from the key a distance less than the travel of the cushioning devices, a coupler at each end of the column, and a shock-absorbing connection between the shank of each coupler and the column.
4. In a railway car having a frame, the combination of a draft and buffing column extending lengthwise of the car and supported for endwise movement on the frame, the column including spaced vertical walls having outer and inner pairs of aligned lengthwise slots adjacent each end of the column, outer and inner keys passing through the respective pairs of slots with their ends anchored on the frame, the keys being substantially narrower than the length of the slots, a pair of cushioning devices of equal travel within the column at opposite ends thereof, each device lying between the outer and inner keys at the adjacent end of the column, a follower mounted on each key and normally engaging the adjacent end of the adjacent cushioning device, stops mounted on the column walls, one at each end of each slot, the pairs of stops between the outer and inner keys at each end of the column normally engaging the ends of the adjacent cushioning device, the stops at opposite ends of the slot for each key being spaced from the key a distance less than the travel of the cushioning device and the stops at the outer ends of the slots for each inner key being spaced farther from said key than the stops at the inner ends of said slots, and a coupler at each end of the column having its shank connected to the column.
5. In a railway car having a frame, the combination of a draft and buffing column extending lengthwise of the car and supported for endwise movement on the frame, the column including spaced vertical walls having outer and inner pairs of aligned openings adjacent each end of the

column, outer and inner keys passing through the respective pairs of openings and anchored at their ends on the frame, the keys being substantially narrower than the length of the openings, a pair of cushioning devices of equal travel within the column at opposite ends thereof, each device lying between the outer and inner keys at the adjacent end of the column, a follower on each key normally engaging the adjacent end of the adjacent cushioning device, stops mounted on the column walls, one at each end of each opening, the pairs of stops between the outer and inner keys at each end of the column normally engaging the ends of the adjacent cushioning device, the stops at opposite ends of the openings for each key being spaced from the key a distance less than the travel of the cushioning devices, a coupler at each end of the column having a shank, a yoke attached to each coupler shank, and a shock-absorbing connection between each yoke and the column.

6. In a railway car having a frame, the combination of a draft and buffering column extending from end to end of the frame and having spaced vertical walls formed with outer and inner pairs of aligned horizontal slots at opposite ends of the column, outer and inner pairs of abutment members secured to the inner faces of said vertical walls to encircle respective pairs of slots, outer and inner keys passing through the respective pairs of slots at each end of the column and anchored at their ends on the frame, the keys being substantially narrower than the length of the slots, a pair of cushioning devices of equal travel between the column walls at opposite ends of the column, each device lying between the outer and inner keys at the adjacent end of the column, a follower on each key normally engaging the adjacent end of the adjacent cushioning device, a stop on each abutment member at each end of each slot, the pairs of stops between the outer and inner keys at each end of the column normally engaging the ends of the adjacent cushioning device, the stops at opposite ends of the openings for each key being spaced from the key a distance less than the travel of the cushioning devices, and a coupler at each end of the column having a shank received between the column walls and secured thereto.

7. In a railway car having a pair of spaced longitudinal sills provided with outer and inner pairs of aligned slots at opposite ends of the sills and a reinforcing member encircling each slot, the combination of a draft and buffering column extending lengthwise of the car between the sills and supported thereby for endwise movement, the column including spaced vertical walls having outer and inner pairs of slots adjacent each end of the column and aligned with the sill slots, outer and inner keys passing through respective pairs of wall slots and having their ends snugly received in the sill slots, the wall slots being substantially longer than the width of the keys passing therethrough, a pair of cushioning devices of equal travel lying between the column walls at opposite ends of the column, each device lying between the outer and inner keys at the adjacent end of the column, a follower on each key normally engaging the adjacent end of the adjacent cushioning device, stops mounted on the opposed faces of the column walls, one stop at the end of each wall slot, the pairs of stops between the outer and inner keys at each end of the column normally engaging the ends of the adjacent cushioning device, the stops at opposite ends of the wall slot for each key being spaced from the key a distance less than the travel of the cushioning devices, restoring spring means secured at spaced points to the sills and column and resisting movement of the column in either direction from a central position, and a coupler at each end of the column having a shank connected to the column.

adjacent cushioning device, the stops at opposite ends of the wall slot for each key being spaced from the key a distance less than the travel of the cushioning devices, and a coupler at each end of the column having a shank received between and connected to the column walls.

8. In a railway car having a pair of spaced longitudinal sills provided with outer and inner pairs of aligned slots at opposite ends of the sills and a reinforcing member encircling each slot, the combination of a draft and buffering column extending lengthwise of the car between the sills and supported thereby for endwise movement, the column including spaced vertical walls having outer and inner pairs of slots adjacent each end of the column and aligned with the sill slots, outer and inner keys passing through respective pairs of wall slots and having their ends snugly received in the sill slots, the wall slots being substantially longer than the width of the keys passing therethrough, a pair of cushioning devices of equal travel lying between the column walls at opposite ends of the column, each device lying between the outer and inner keys at the adjacent end of the column, a follower on each key normally engaging the adjacent end of the adjacent cushioning device, a reinforcing member mounted on the inner face of each column wall to encircle each slot through the wall, stops on the wall reinforcing members, one stop at the end of each wall slot, the pairs of stops between the outer and inner keys at each end of the column normally engaging the ends of the adjacent cushioning device, the stops at the opposite ends of the wall slot for each key being spaced from the key a distance less than the travel of the cushioning devices, and a coupler at each end of the column having a shank attached to the column walls.

9. In a railway car having a pair of spaced longitudinal sills provided with outer and inner pairs of aligned slots at opposite ends of the sills and a reinforcing member encircling each slot, the combination of a draft and buffering column extending lengthwise of the car between the sills and supported thereby for endwise movement, the column including spaced vertical walls having outer and inner pairs of slots adjacent each end of the column and aligned with the sill slots, outer and inner keys passing through respective pairs of wall slots and having their ends snugly received in the sill slots, the wall slots being substantially longer than the width of the keys passing therethrough, a pair of cushioning devices of equal travel lying between the column walls at opposite ends of the column, each device lying between the outer and inner keys at the adjacent end of the column, a follower on each key normally engaging the adjacent end of the adjacent cushioning device, stops mounted on the opposed faces of the column walls, one stop at the end of each wall slot, the pairs of stops between the outer and inner keys at each end of the column normally engaging the ends of the adjacent cushioning device, the stops at opposite ends of the wall slot for each key being spaced from the key a distance less than the travel of the cushioning devices, restoring spring means secured at spaced points to the sills and column and resisting movement of the column in either direction from a central position, and a coupler at each end of the column having a shank connected to the column.

STANLEY H. FILLION.
